United States Patent Office.

HOWARD M. THOMPSON AND CHARLES W. BURBANK, OF ALFRED, MAINE, ASSIGNEES
TO THEMSELVES AND GEORGE H. KNOWLTON, OF SAME PLACE.

Letters Patent No. 81,959, dated September 8, 1868.

IMPROVEMENT IN TAILORS' PRESS-BOARDS.

The Schedule referred to in these Letters Patent and making part of the same.

TO ALL PERSONS TO WHOM THESE PRESENTS MAY COME:

Be it known that we, HOWARD M. THOMPSON and CHARLES W. BURBANK, of Alfred, in the county of York, and State of Maine, have made a new and useful invention having reference to Press-Boards for the Use of Tailors or others; and we do hereby declare the same to be fully described in the following specification, and represented in the accompanying drawings, of which—

Figure 1 denotes a top view,

Figure 2 a side elevation, and

Figure 3 a longitudinal section of the invention as applied to a table.

In carrying out our invention, we combine with a common press-board a means or mechanism for supporting it over the top of a table, and clamping it thereto. Our invention also includes such means as are operated by the gravitating-power of the board, and by the pressure which is exerted on the board while it may be in use.

In the drawings, A denotes a table, and B a tailor's press-board, such as is generally introduced into the leg of a pair of pantaloons or the sleeve of a garment, to enable a person to press down with a flat-iron or "tailor's goose" the folds of the seam.

The said press-board rests on the top of a standard, C, erected on a base-board, D, at or near the middle thereof. The said press-board extends underneath a flat arm, E, which is pivoted to the opposite edges of the standard by means of two projections, *a a*, and by a screw, *b*, going through each of them, and being screwed into the standard.

A clamp-jaw, F, hinged to the base-board, at or near its outer end, extends underneath the table-top in manner as represented, and is connected with the arm E by means of a rod, *c*, such rod being hinged or jointed to the clamp-jaw, and extended up through a slot, *d*, made in the base-board.

The connection-rod has a screw, *e*, cut on it, which goes through the arm E, and receives a nut, *f*, arranged on the top of the said arm.

By forcing the press-board downward, the arm E will be raised, so as to draw the clamp-jaw close up to table-top, and at the same time press the base-board down upon such top. Thus, it will be observed, that the weight of the longer part of the press-board which extends from the standard, together with a pressure on such part, will operate to clamp the board in position on the table.

The purpose of the screw *e* and nut *f* is to enable the press-board supporter to be adjusted to boards and table-tops according as they may vary in thickness; also, to adjust the press-board either to a horizontal position, or such an inclination as circumstances may require.

We claim the press-board supporter substantially as described, that is, as composed of the base-board D, the standard C, the arm E, and the clamp-jaw F, connected in manner so as to operate as explained.

We also claim the combination and arrangement of the adjusting-screw *e* and nut *f* with the connection-rod *c*; the clamp-jaw F, the base-board D, the standard C, and the arm E, arranged and combined substantially in manner and for the purpose as specified.

We also claim the combination of the press-board B, and mechanism, substantially as described, for supporting it above, and fixing or clamping it to a table, as explained, such mechanism consisting of the base-board D, the standard C, the arm E, the clamp-jaw F, and the connection-rod *c*, or their mechanical equivalents.

HOWARD M. THOMPSON,
CHARLES W. BURBANK.
